INVENTOR -

George F. Voight.

UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

FURRING UNIT.

Application filed September 26, 1923. Serial No. 664,897.

My invention relates to furring units useful for securing plastic reinforcement to the wall sheathing of frame buildings, although also useful for other purposes.

- 5 An object of the invention is the provision of a disk-like spacing element formed by wrapping a strip of paper a sufficient number of times around the forward end of a driven element, the spacing element operatively 10 slidable on the driven element for co-operating with a side arm on the latter for clamping the reinforcement therebetween when applying the latter to the wall sheathing.
- 15 A further object is the provision of a spacing element formed of fibrous material having a certain amount of flexibility so as to form a seat for the reinforcement wire that is somewhat yielding and whereby 20 the spacing element will not injure the reinforcement by cutting or crushing it in case the latter is forced down thereupon 25 recessively by the excessive driving of the driven element.
- 25 A still further object is the provision of a solid spacing element formed of yielding fibrous composition and having a lower flat side adapted to seat against the face of the building paper, in case the latter is applied 30 to the wall sheathing of the structure, and firmly bound against said building paper by the driven element, whereby water or moisture will be prevented from penetrating or leaking between said spacing element and 35 building paper.
- 40 A still further object is the provision of a furring unit comprising a driven element projecting axially through a disk-shaped spacing element, the latter having upper and lower flat sides disposed in parallel relation, thereby providing the spacing element with 45 a lower seating surface approximately equal in dimensions to the area of its lower side, and an upper wire receiving surface approximately equal to the area of its upper side and extending from the sides of said driven element laterally in any direction to the rim of the spacing element.
- 50 With the foregoing and still further objects and purposes in view which will appear as the description proceeds, my invention resides in the combination and arrangement of parts and in the details of construction hereinafter described and claimed, it 55 being understood that changes in the precise

embodiment of the invention herein disclosed can be made within the scope of what is claimed without departing from the spirit of the invention.

In the accompanying drawings—

Figure 1 is a side elevation of a furring unit constructed in accordance with my invention, in its initial position as disposed against the wall sheathing of a structure, also showing a cross section of one of the wires forming a portion of the plastic reinforcement;

Figure 2 is a central vertical section of the furring unit, a cross section of the reinforcement wire and a section through a fragment of the wall sheathing;

Figure 3 is a side view of the invention in its permanent position as secured to the wall sheathing, with the spacing element moved into operative engagement with the side arm at the upper end of the driven element, and a section of the reinforcement wire confined between the spacing element and arm;

Figure 4 is a view on line 4'-4', Fig. 1;

Figure 5 is a plan view of the device;

Figure 6 is a view of a paper ribbon from which the spacing disk is preferably formed;

Figure 7 is a side elevation of the driven element and a paper ribbon wrapped partly therearound for forming the spacing element; and

Figure 8 is a greatly enlarged view of the furring unit approximately on line 8'-8', Fig. 7, showing method of forming the spacing disk by wrapping the paper ribbon around the driven element.

Referring to the drawings in detail, throughout which like reference characters designate like parts:

The numeral 1 designates a representation of the wall sheathing of a frame building, which forms the backing or base against which is adapted to be spread an outer coat of plastic composition, 2 the furring unit, and 3 a wire forming a portion of the plastic reinforcement, the latter comprising, preferably, wire cloth commonly known as "poultry netting."

The furring unit 2 embodies a driven element 4 comprising a shank member 5 having its upper end bent to one side to form a downwardly projecting side arm 6, and a spacing element 7 comprising a strip of paper 8, which is wrapped "flat-ways" around the shank member 5 in continuously

receding coils disposed in tightly wound order in a common plane, with the first coil upon the periphery of the shank, the second coil on the first coil, and so on throughout the length of the strip until a disk-like element of proper diameter is formed.

It is preferable that the paper, previous to wrapping it around the shank 5, be subjected to a treatment of heated bitumen pitch or the like, as a preservative against disintegration from atmospheric dampness or dampness directly applied by the spreading thereon of the wet plastic materials when the latter is operatively applied to the wall. The said treatment being intended to also provide sufficient adhesive to the sides of the paper strip so that the several coils into which the paper is rolled in forming the spacing element will adhere to each other and thereby remain in a tightly rolled-up condition on the shank.

After the paper has been tightly and permanently rolled onto the shank 5, it is preferable to immerse the unit in hard-drying asphaltum varnish or the like, so as to impart thereto a certain amount of rigidness and to cause it to adhere to the shank and become normally locked thereon against accidental movement when the units are packed in the bulk into receptacles for purposes of transportation or the like, or when handled as when applying them operatively to the sheathing boards, but vertically slideable on the shank by disrupting the adhesive seal between the latter and the spacing element when the latter is disposed against the wall sheathing and the shank operatively driven thereinto.

It is preferable to have the spacing element factory-built onto the forward end of the driven element and carried thereby (see Figs. 1 and 2), and slideable vertically to the upper end of the shank against the resistance of the adhesive only when the furring unit is operatively applied to the wall sheathing for securing the reinforcement.

It is frequently desirable to dispose building paper against the wall sheathing before applying the furring units and reinforcement. The building paper coats with the wall sheathing in forming a base for the plastic composition. In case of the application of the building paper as aforesaid, it will be found that the paper spacing disks of my furring unit, being of yielding quality, may be forced thereagainst without cutting or injuring it in the least however excessively the shank may be driven. It is common occurrence in applying all metal furring units, particularly those having sheet metal spacing devices, such as the devices disclosed in Patents 383,952; 1,311,932 and 1,435,429, as well as the Wagner-Behm device shown in Engineering News of Aug.

5, 1915, over building paper, to not only cut and damage the same, but all these devices fail to effect definite or precise furring for the reinforcement for the reason that when the shank element is accidentally driven excessively, it causes the comparatively narrow edges of the sheet metal spacing elements to penetrate the wall sheathing to a more or less degree.

It is to be understood that, while I prefer to roll or wrap the paper strip directly on and around the shank of the driven element in forming the spacing element, it can be formed separately and the shank afterwards projected through a central opening therein.

It is further to be understood that I do not desire to restrict myself to the particular method described of temporarily locking the spacing element on the forward end of the shank by adhesion, but instead, if desired, the spacing element may be retained on the shank by tightly embracing it and held against movement by the friction of the one element bearing against the other.

It is obvious that any number of the furring units may be employed in securing a section of the reinforcement.

To apply my device to the wall sheathing, the furring unit is projected forwardly through one of the meshes of the reinforcement from the outer side and the point of the shank engaged with the sheathing with the body of the shank disposed along one side of one of the wires of the mesh (see Figs. 1 and 2), the shank is then driven into the sheathing until the side arm engages said wire from the upper side and forces it down firmly upon the upper end of the spacing element and thereby permanently holds it thereagainst. The plastic composition being adapted to be spread on the wall sheathing and on and around the reinforcement and the protruding portions of the furring units.

I claim:

1. In means of the character described, building paper adapted to be secured to a support, a yielding spacing element formed of fibrous composition and having a flat side seated against the face of said building paper, and means projecting through said spacing element and said building paper and adapted to be projected in said support for binding said spacing element firmly against said building paper whereby moisture is prevented from penetrating therebetween to said means below said spacing element.

2. A furring unit comprising a driven element and a substantially cylindrical spacing element, said spacing element formed of a strip of paper bound on and around the shank of said driven element, to normally resist removal therefrom.

3. The combination with a driven element having a side arm at its upper end, of a

spacing element encircling the forward end of said driven element and normally locked thereon against vertical movement relative thereto by means of an adhesive element applied to both said first named elements, said adhesive element adapted to rupture and the spacing element adapted to slide vertically along said driven element into operative co-operation with said side arm when said driven element is operatively projected a proper distance in a support, said spacing element formed of fibrous material.

4. A furring unit comprising, a solid spacing element cylindrical in cross section and of equal diameter throughout, and a driven element projecting therethrough, said spacing element being formed of paper composition and provided with a coating of bitumen pitch or the like to prevent dampness penetrating to the interior thereof. 15

In testimony of the foregoing being my own, I have hereunto affixed my signature this 19th day of September, 1923.

GEORGE F. VOIGHT.
